(57) **CLAIM**

We hereby claim the design for a breast milk pump, as shown and described.

DESCRIPTION

FIG. 1 is an isometric view of a breast milk pump showing our design;

FIG. 2 is a front view thereof;

FIG. 3 is a right view thereof;

FIG. 4 is a top view thereof;

FIG. 5 is a left view thereof;

FIG. 6 is a bottom view thereof; and,

FIG. 7 is a back view thereof.
